UNITED STATES PATENT OFFICE.

CHARLES E. NORTON, OF NORFOLK, VIRGINIA, ASSIGNOR OF ONE-HALF TO
C. F. PENDLETON, OF SAME PLACE.

AIR-INJECTOR FOR FURNACES.

SPECIFICATION forming part of Letters Patent No. 556,687, dated March 17, 1896.

Application filed July 23, 1895. Serial No. 556,887. (No model.)

To all whom it may concern:

Be it known that I, CHARLES E. NORTON, of Norfolk, in the county of Norfolk and State of Virginia, have invented certain new and useful Improvements in Steam-Boiler Furnaces; and I do hereby declare that the following is a full, clear, and exact description of the invention, which will enable others skilled in the art to which it appertains to make and use 5 the same, reference being had to the accompanying drawings, and to the letters of reference marked thereon, which form part of this specification.

This invention relates to certain improvements in furnaces, such as steam-boiler furnaces, and more particularly to draft or combustion promoting devices for furnaces.

The object of the invention is to provide an improved draft-accelerating device for furnaces simple, durable and effective in construction and generally applicable to furnaces, and wherein a series of steam-jets create a strong draft into the furnace in such a way as to promote the draft through the burning fuel whether the blast be introduced beneath and passed through the fire or be introduced in the flues or smoke-passages beyond the fire to create a suction through the same.

The invention consists in certain novel features of construction and in combinations and arrangements of parts more fully and particularly pointed out and described hereinafter.

Referring to the accompanying drawings, Figure 1 is a front elevation of a steam-boiler furnace, showing different ways of applying my invention thereto. Fig. 2 is a detail elevation of the blast-injector. Fig. 3 is a longitudinal section thereof. Fig. 4 is a detail elevation of the perforated steam-chamber. Figs. 5 and 6 are detail sectional views showing different ways of forming the annular steam-chamber.

In the drawings, *a* is a furnace having ash-pit *b* beneath the usual grate and combustion-chamber and an offtake *c*. *d* is the furnace-front, and *e* the brick or masonry setting of the furnace.

The blast-injector can be arranged at any suitable point on the furnace so as to discharge the air-blast beneath the grate or up

into the smoke-offtake, so as to force the increased draft through the grate or create an increased draft by suction in the uptake.

Fig. 1 shows the draft-injectors *f* extending through the furnace-front, and also through the side casing or setting and discharging into the space beneath the grate, and also an air-injector arranged at the exterior of the casing of the furnace with the air-pipe therefrom extending upwardly and into the smoke-uptake to increase the draft and suction at that point.

The air-injector consists of the barrel, pipe or hollow cylinder *g*, having the annular offset or enlargement *g'* at its outer end, forming an enlarged annular seat having perforated radial ears *g²* at its outer edge. This cylinder is open throughout and at both ends.

h is an outwardly-flaring mouth or nozzle on the outer end of the cylinder and provided with the annular surrounding flange *h'* at its inner end and the lateral perforated ears *h²* to register with gears *g²* and receive securing-bolts. This flange *h'* forms the outer wall of the offset or seat *g'* in the outer end of the cylinder.

A steam-chamber *i* is located removably in said seat *g'*. This chamber *i* consists of a ring-shaped casting, U-shaped in cross-section and of such dimensions as to snugly fit in said chamber when its cap *i'* has been secured thereon. This cap *i'* is formed with a projecting edge *i²* to fit and be clamped between the flange *h'* and the end of the cylinder and with a raised circular rib *i³* on its inner face screw-threaded at both edges to screw into and close the open side of the steam-chamber.

The inner corner of the steam-chamber is provided with the series of inwardly-inclined steam-jet holes or openings *i⁴* opening from the steam-chamber into the interior of the cylinder and all inclined inwardly toward the inner end of the cylinder.

j is a steam-supply pipe from the boiler *k* opening through the offset of the cylinder and the steam-chamber and supplying the steam thereto.

The circular series of steam-jets around the interior of the cylinder, all inclined inwardly

and usually and approximately toward a common center, form such a vortex and suction as to draw a powerful and heavy blast of air in through the funnel-shaped mouth and 5 through the cylinder into the ash-pit or into the smoke-flue, or wherever desired.

In Fig. 1 one of the injectors is shown supported in a vertical position with its mouth down and with the pipe extended upwardly 10 and into the smoke-pipe.

The device is so constructed that it can be easily made and put together and so that the parts can be removed and cleansed or for examination without trouble.

15 I do not limit myself to any particular location of the injector, nor to use in any particular connection, nor to the particular construction shown and described, as various changes can be made without departing from the spirit 20 and scope of my invention.

In Fig. 5 the cap or plate closing one end 25 of the annular steam-chamber is shown with rib i^5 to fit in the open end of said chamber and close the same without the employment of the screw-threads. Packing i^7 can be in-

serted between said cap and the outer edge of the chamber if so desired.

In Fig. 6 the outer wall of the chamber is formed by the enlarged end of the cylinder or pipe g and an end wall by the rib i^5 of the closing-cap. The other two walls of the casing are formed by a ring i^8 , L-shaped in cross-section and corresponding to the wings in the other views, except being L-shaped instead of U-shaped in cross-section.

What I claim is—

A barrel having the annular seat at its outer end, the ring-shaped steam-chamber therein having the series of jet-openings at its inner side, and the ring closing its open side and provided with an exterior rim, and the mouthpiece secured to the barrel and clamping said rim, substantially as described.

In testimony that I claim the foregoing as my own I affix my signature in presence of two witnesses.

CHARLES E. NORTON.
